UNITED STATES PATENT OFFICE.

FRANK A. KENNEY, OF DENVER, COLORADO.

ARTIFICIAL ARM.

Application filed November 19, 1923. Serial No. 675,550.

To all whom it may concern:

Be it known that I, FRANK A. KENNEY, in position across the back so as to show the a citizen of the United States, residing at hinge nearest the body;

5 State of Colorado, have invented certain Fig. 3 is a side view showing the arm new and useful Improvements in Artificial extended for opening the hook;

10 in the art to which it appertains to make Fig. 4 is a rear view showing the arm in new and useful Improvements in Artificial extended position;

15 This invention relates to artificial arms Fig. 5 is a view taken in the direction of of the type disclosed and claimed in Patent arrow 5 in Fig. 1 and shows a portion of No. 1,472,177 granted to me October 30, the arm on a larger scale;

20 and has special reference to improvements which will particularly adapt the Fig. 6 is a section taken on line 6—6, arm to the needs of persons having their Fig. 1;

25 arm amputated above the elbow.

Artificial arms that are to be worn by those who have "above the elbow amputations" naturally require a different mechanical construction than those where the wearer has the arm amputated between the elbow and the wrist. In the latter case the wearer can flex the arm by his own efforts, while in the former case, mechanical means must be provided for flexing the arm. Where the artificial arm is provided with mechanical flexing means, it is also necessary to provide locking means for retaining the arm in flexed position and for permitting the arm to straighten out at any time. Where the arm is provided with a hook that can be opened and closed, it is also necessary to provide means that will prevent the arm from bending while the hook is being opened.

It is the object of the present invention to produce an artificial arm which shall embody the invention described and claimed in my above-referred to patent, and which, in addition thereto, shall also have the above-referred to mechanisms for adapting it for use by persons whose arms are amputated above the elbow.

In order better and more clearly to describe my invention, I shall have reference to the accompanying drawings in which my improved arm is illustrated in its present preferred form, and in which:

Fig. 1 is a front view of a man equipped with my improved artificial arm;

Fig. 2 is a rear view showing the arm in position across the back so as to show the hinge nearest the body;

60 Fig. 3 is a side view showing the arm extended for opening the hook;

Fig. 4 is a rear view showing the arm in extended position;

Fig. 5 is a view taken in the direction of arrow 5 in Fig. 1 and shows a portion of the arm on a larger scale;

65 Fig. 6 is a section taken on line 6—6, Fig. 1;

Fig. 7 is a section taken on line 7—7, Fig. 1;

70 Fig. 8 is a view looking in the direction of arrow 8, Fig. 4;

Fig. 9 is a section, through the outside hinge, taken on line 9—9, Figs. 5 and 6;

75 Fig. 10 is a section, through the inside hinge, taken on line 10—10, Figs. 7 and 8;

Fig. 11 is a section through the cam;

Fig. 12 is a side elevation showing the ratchet member that is secured to the cam;

80 Fig. 13 is a side elevation of the operating pulley, looking in the direction of arrows 13—13, Fig. 10; and

Fig. 14 is a view of the operating pulley taken along line 14—14, Fig. 10.

The same reference characters will be used to designate the same parts throughout the several views.

As mentioned in the foregoing portion of this specification, this invention relates to an artificial arm to be used by persons having their arm amputated above the elbow and this should be borne in mind while reading the following description. The arm is formed in two sections A and B, the former of which will be referred to as the upper arm section and the latter the forearm section.

These sections are connected by means of hinges that will be described in detail in following portions of the specification. The upper arm, section A, is hollow and receives the stub of the arm in the usual way. In order to hold the arm in place so that it can be freely moved into any position and at the same time be prevented from being pulled off, I employ the harness described and claimed by me in my patent above identified. This harness, briefly described, consists of a web which has one end, indicated by numeral 1, terminating at the back of the shoulder and the other end, indicated by numeral 2, terminating on the front near

the armpit. The web crosses at the back and loops around the shoulder on the opposite side of the body from that to which the arm is secured. A cord 3 is secured to end 5 1 and passes through loop 4 on section A. It then extends upwardly under the arm, passes through the loop 5, secured to end 2, and thence downwardly and is anchored to section A at point 6. The advantages of 10 this way of securing an artificial arm in place is fully explained in my former patent. The forearm section 13 is provided with a hook 7 that has a movable jaw 8. This hook is normally held in closed position by elastic bands or other means, not shown. For the purpose of opening the jaws of the hook, I connect a cord 9 to the end of the lever 10. This cord has its other end connected to the web at point 11 and 15 has its effective length adjusted by means of the buckle 12. Cord 9 passes through a loop 13 on section A and also through another loop 14, the purpose of which will be hereinafter explained. When the arm is extended, cord 9 will be put under tension and 20 will open the jaws of hook 7. Since the wearer has his arm amputated above the elbow, he has nothing with which to control the forearm section B and since sections A 25 and B are hinged at the elbow, it is evident that any tension in cord 9 will tend to flex the arm at the elbow joint and thus prevent the jaws of the hook from being 30 opened. I have therefore provided means 35 that will operate to lock the sections A and B against movement about the elbow hinge as soon as the cord 9 is tensioned. Referring now more particularly to Figs. 5, 6 and 9, it will be noted that I have secured 40 to the upper end of section B a hinge portion, which cooperates with another portion 16 secured to the lower end of section A. A pin 17 passes through parts 15 and 16 and also through an opening in the lower end of 45 part 18. The parts just described form the outer hinge. Part 18 has its lower end curved in the arc of a circle and is provided with a number of notches 19. A pawl 20 is 50 non-rotatably secured to a pintle 21, which extends outwardly through the hinge member 15 and has a lever 22 non-rotatably connected to the outer end thereof so that the lever 22 and the pawl 20 will move as a 55 unitary structure. A spring 23 is secured to the pawl and is tensioned to hold the pawl in inoperative position in the manner shown in Fig. 6. The loop 14 is connected to the 60 end of the lever 22 and when cord 9 is put under tension it turns lever 22 and pawl 20 about their common pivot and moves the pawl into operative engagement with the teeth or notches 19 and locks sections A and B against relative movement. As soon as 65 the tension in cord 9 subsides, the spring 23 moves the pawl to inoperative position.

From the above description, it will now be apparent that when the wearer of the artificial arm wants to open the jaws of the hook, he merely extends the arm so as to tension cord 9. As soon as cord 9 is tensioned, 70 it will move pawl 20 into locking position and prevent sections A and B from turning about the elbow, after which the jaws will open.

Since the wearer has no forearm portion, 75 he has no means of flexing the arm sections. I have therefore provided the following described means for this purpose. A cord 24 has one end secured to end 1 of the harness web. This cord passes through an opening 80 25 in section A over a pulley 26 secured to the front side of section A near the bottom thereof, and has its other end fastened to section B at point 27 (Fig. 6). It is evident that when cord 24 is put under tension, 85 it will tend to bend the arm at the elbow and the necessary tension for this can be obtained by a suitable movement of the arm.

It is often desirable to maintain the arm sections in flexed position so that a coat may 90 be carried on the forearm or for any other purpose. In order to lock the arm in flexed position, I have provided the following means:

The inside hinge shown in section in Fig. 95 10 has one member 28 (similar to member 15) secured to the outside of the forearm near the elbow portion thereof and has a cooperating hinge portion 29 secured to the lower end of section A. Sections 28 and 100 29 are joined by a pin 30. A section 31 (similar to 18) is secured to the inside of section A and has an opening for the reception of pin 30. The lower end 32 of part 31 is provided with a plurality of 105 ratchet teeth 33 (Fig. 7). A pawl 34 is pivoted at 35 and has a spring 36 secured to its free end and tensioned to move the pawl into engagement with the ratchet teeth 33. An eccentric cam 37 is pivotally mounted in the manner indicated in Fig. 9. When the cam is in the position shown in Fig. 7, it permits the pawl 34 to become effective and to engage the ratchet teeth 33, 110 but when the cam is turned 180 degrees, it holds the pawl in inoperative position. The cam has two diametrically opposed ratchet teeth 38, which cooperate with the spring-actuated pawl 39, to prevent rotation of the cam in one direction. The cam has fastened thereto a ratchet plate 40 provided with diametrically opposed notches 41. The connection 42 between the pawl and the cam is hollow for the reception of the bolt 43. For the purpose of ratcheting the cam and for rotating it into operative and inoperative position, I have provided a ratchet pulley 44, which has a circular recess 45 on its inner side for the reception of ratchet disk 40. Within recess 45 are a pair of 115 120 125 130 135

diametrically opposed teeth 46 which engage one edge of notches 41 and rotate the cam 37 when the pulley rotates in one direction, but which slide over the disk 40 when the pulley rotates in the opposite direction. A housing 47 encloses the pulley 44. A stop 49 on the pulley cooperates with suitable stops in the casing 47 for the purpose of limiting the rotation of the pulley to approximately 180 degrees. A cord 48 has one end secured to the pulley and the other end secured to the end 2 of the harness web. When the arm is placed in such a position that cord 48 is tensioned, pulley 44 is rotated in one direction and the cam 37 is turned. When the tension is removed from cord 48, a spring 50, which lies in the recess 51, rotates the pulley in the opposite direction and winds the cord onto the pulley. If we assume that the cam is in the position shown in Fig. 7, then the first pull on cord 48 will rotate the cam 180 degrees and move the pawl 34 to inoperative position. The second pull on cord 48 will return the cam to the original position. Thus alternate pulls on cord 48 renders the pawl 34 alternately operative and inoperative.

Let us now assume that the arm is hanging straight down by the wearer's side and that he desires to bend the same. He will move the arm so as to tension cord 24. This will flex the arm, which will be held in flexed position by pawl 34. When the wearer desires to straighten the arm, he will move it so as to tension cord 48, thereby rotating cam 37 and moving pawl 34 to inoperative position, when the arm sections are free to move into straightened position. The arm can now be bent and straightened at will and can be locked in bent position by the simple expedient of putting tension in cord 48.

When the amputation is below the elbow, an arrangement comprising cords 24 and 48 may be used to operate the hand at the wrist, substantially the same means being employed.

Where the wearer has a short stub of his forearm, which, however, is not long enough to serve as a means for flexing the artificial arm, the cord 24 may be made double on the inside of the arm sections and pass on the sides of the arm.

From the above description, it is apparent that I have produced an arm having means to open a hook and to lock the same against flexure. It has also means for flexing the arm and for locking it in flexed position, together with means for rendering said lock inoperative.

Having now described my invention, what I claim as new is:

1. An artificial arm comprising, in combination, a section adapted to be secured to

the upper arm, a forearm section hingedly connected thereto, means for securing the arm to the wearer, means for flexing the arm, separate means for limiting the amount of flexure to any extent desired, and resilient means for normally holding said limiting means in inoperative position. 70

2. An artificial arm comprising, in combination, a section adapted to be secured to the upper arm, a forearm section hingedly connected thereto, means for securing the arm to the wearer, means for flexing the arm, separate means for holding the arm in flexed position, and means comprising a cam for alternately rendering said holding 80 means operative and inoperative.

3. An artificial arm comprising, in combination, a section adapted to be secured to the upper arm, a forearm section hingedly connected thereto, means for securing the arm to the wearer, means for flexing the arm, separate means for holding the arm in flexed position, and means comprising a cam for alternately rendering said holding 85 means operative and inoperative, said means comprising a step by step mechanism. 90

4. An artificial arm comprising, in combination, a section adapted to be secured to the upper arm, a forearm section hingedly connected thereto, means for securing the arm to the wearer, a hook carried by the forearm section, means for opening said hook, and means operated by said opening 95 means for limiting the extent of flexure of 100 said arm sections.

5. An artificial arm comprising, in combination, a section adapted to be secured to the upper arm, a forearm section hingedly connected thereto, means for securing the arm to the wearer, a hook carried by the forearm section, means for opening said hook, means operated by said opening means for limiting the extent of flexure of said 105 arm sections, and resilient means for rendering said flexing means inoperative. 110

6. An artificial arm comprising, in combination, a section adapted to be secured to the upper arm, a forearm section hingedly connected thereto, means for securing said arm to the wearer, means for flexing said arm, a hook member secured to the forearm section, means for opening said hook member, resilient means for closing said hook member, and means operated by the hook 115 member, and means operated by the hook opening means for limiting the flexing of 120 the arm.

7. An artificial arm comprising, in combination, a section adapted to be secured to the upper arm, a forearm section hingedly connected thereto, means for securing said arm to the wearer, means for flexing said arm, a hook member secured to the forearm section, means for opening said hook member, resilient means for closing said hook member, 125 130

means operated by the hook opening means for limiting the flexing of the arm, and resilient means for normally holding said limiting means in inoperative position.

5. 8. An artificial arm comprising, in combination, a section adapted to be secured to the upper arm, a forearm section hingedly connected thereto, means for securing said arm to the wearer, means for flexing said arm, a 10 hook member secured to the forearm section, means for opening said hook member, resilient means for closing said hook member, means operated by the hook opening means for limiting the flexing of the arm, means 15 for holding said arm in flexed position, and means for rendering said holding means operative or inoperative at will.

9. An artificial arm comprising, in combination, a section adapted to be secured to the 20 upper arm, a forearm section hingedly connected thereto, a harness for securing the arm to the wearer, said harness comprising a strap enclosing the shoulder opposite from the arm, said strap crossing at the wearer's 25 back and having its ends terminating near the shoulder to which the arm is attached, means for flexing said arm, said means comprising a cord attached to one end of said harness near the artificial arm, means for 30 holding said arm in flexed position, and means for rendering said holding means operative or inoperative at will, said means comprising a cord having one end connected to the other end of said harness and the 35 other end connected to a pawl and ratchet mechanism.

10. An artificial arm comprising, in com-

bination, a section adapted to be secured to the upper arm, a forearm section hingedly connected thereto, a harness for securing the 40 arm to the wearer, said harness comprising a strap enclosing the shoulder opposite from the arm, said strap crossing at the wearer's back and having its ends terminating near the shoulder to which the arm is attached, 45 means for flexing said arm, said means comprising a cord attached to one end of said harness near the artificial arm, means for holding said arm in flexed position, means for rendering said holding means operative 50 or inoperative at will, said means comprising a cord connected to the other end of said harness, a hook carried by said forearm, resilient means for holding said hook closed, and means for locking said arm against 55 flexure, said means also opening said hook.

11. An artificial arm comprising, in combination, a section adapted to be secured to the upper arm, a forearm section hingedly connected thereto, means comprising webbing 60 for securing the arm to the wearer, means for flexing the arm by means of a cord attached to the webbing, at rear of shoulder next to the artificial arm, a hook, 65 means for operating said hook from cord across the back attached to supporting harness at shoulder opposite artificial arm, and means for locking forearm in any position relative to the upper arm, said means comprising the means for operating hand or 70 hook.

In testimony whereof I affix my signature.

FRANK A. KENNEY.
